WINDING MACHINE

Edward F. Parks, Providence, R. I., assignor to
 Universal Winding Company, Boston, Mass., a
 corporation of Massachusetts

Application April 27, 1934, Serial No. 722,771

17 Claims. (Cl. 242—43)

This invention relates to winding machines for winding packages of yarn, thread and the like, and particularly to a device or attachment for adapting the machine to wind on a spool, bobbin or yarn-carrier having a tapered head, with the layers of winding arranged concentrically and disposed to follow the incline of the head of the spool or bobbin whereby the outer end of the package assumes a pointed or tapered shape.

One object of the invention is to provide a device or attachment of the type indicated which may be readily applied to winding machines of standard design without material alteration in the construction or arrangement thereof.

Another object of the invention is to provide a device or attachment of the type indicated having means for axially shifting the spool, bobbin or carrier on which the package is wound to displace the layers of winding longitudinally of the spool with the shifting means controlled from the growth of the winding without dependence upon or connection with the traversing thread-guide of the machine.

Another object of the invention is to provide a device or attachment of the type indicated wherein the shifting of the spool, bobbin or carrier is effected automatically by means contacting with the winding and movable by the increase in diameter thereof without exerting undue pressure and friction upon the mass being wound.

Another object of the invention is to provide a device or attachment of the type indicated wherein the spool, bobbin or yarn-carrier is shifted by the action of a single member in the nature of a bell-crank lever moved by and with the growth in the winding.

Further objects of the invention are set forth in the following specification which describes a preferred form of construction of the winding device or attachment, by way of example, as illustrated by the accompanying drawings. In the drawings:

Fig. 1 is a side elevation of a winding machine of well known type illustrating the present improved device or attachment as applied to use therewith;

Fig. 2 is an enlarged plan view of the present improved device or attachment showing it in connection with the spindle and traversing thread-guide of the winding machine and illustrating the position of the parts at the start of winding a package;

Fig. 3 is a similar plan view showing the position of the parts at the completion of the pack-

age;

Fig. 4 is an end view of the winding-spindle showing the relation of the parts of the present device thereto; and

Fig. 5 is a side elevation of a portion of the winding machine viewed from the rear and showing the present device with the contact-roller raised away from the winding-spindle to facilitate the placing of the spool, bobbin or cop-tube thereon and the removal of the completed package therefrom.

In essence, the present invention consists in a mandrel or holder for the spool, bobbin or carrier slidably mounted on the winding-spindle or drive-shaft of the machine and connected with a bell-crank lever which is adapted to be rocked by means bearing on the yarn mass being wound to shift the mandrel to displace the layers of winding axially of the spool, bobbin or carrier.

For convenience of description, the wound spool, bobbin or the like is hereinafter referred to as a "package", the material being wound into the package, whatever its nature, is designated "yarn"; and the carrier for the package called a "tube". It is to be understood, therefore, that these terms are to be interpreted severally in their generic sense as indicating any type of thread package, all kinds of strand material, and any preferred shape of core or carrier on which the material is wound.

It has heretofore been proposed to provide an attachment for winding machines having means controlled by the growth of the yarn mass being wound to shift the package longitudinally to displace the layers of winding axially thereof. The purpose of such devices is to form the package convexly at one end with a correspondingly concaved opposite end, in some cases without the employment of a cop-tube or carrier having a tapered head or base, as in winding certain forms of cone packages; and in other instances, with the use of a bobbin, cop-tube or yarn-carrier having a tapered base.

In all devices heretofore used for this purpose there is great complication of the mechanism, such as articulated levers, links, slides and the like, with numerous joints liable to become worn and shackle to thereby destroy the accuracy of control of the winding. In one previously patented device the shifting of the spool is effected by the movement of the thread-guide away from the axis of the package during the growth in the winding, but such a form of construction, besides being complicated, has the disadvantage of increasing the pressure of the guide on the package to cause bulging or malformation at its end.

In another form of construction, where the means for shifting the spool or bobbin is operated by a presser-plate bearing against the winding, there is also undue pressure exerted on the yarn mass 5 which has a deleterious effect, especially in winding soft yarns.

In the present invention, by reducing the mechanism to practically only one operating element, for example, a bell-crank lever movable by and 10 with the growth of the winding, friction and resistance is materially reduced and the wound mass is relieved of undue pressure and abrasive rubbing action on its surface.

In the present drawings the improved device 15 is shown as applied to the standard type of winding machine identified by the trade-mark "Universal". Referring to Fig. 1, the winding machine comprises a main frame 2 of box-like construction provided with opposite bearings 3 20 at the top, in which is journaled a shaft 4, usually termed the "winding-spindle". Arranged below and parallel with the winding-spindle 4 is a cam-shaft 5 journaled in bearings 6 at the sides of the frame 2. The spindle 4 constitutes 25 the drive-shaft of the machine, being driven from a belt-pulley 8 adapted to be connected therewith through a clutch-member 9 fast on the shaft. The clutch-member 9 is integral with a belt-pulley 10 which is connected by a belt 11 to a 30 similar pulley 12 located therebelow. The pulley 12 is fast with and drives a shaft 13 journaled in a bearing 14 in a casing 15 at the side of the main frame 2. At its inner end the shaft 13 carries a pinion 16 meshing with a gear 17 fast on 35 the end of the cam-shaft 5.

Fast on the cam-shaft 5 is a cam 20 having a helical groove 21 in its periphery. The groove 21 is engaged by a roller or follower 22 on a slide or crosshead 23 which constitutes the means for 40 reciprocating the thread-guide 25. The crosshead 23 is slideable in a guideway in a traverse-frame 26 constituted by a horizontal bar 27 supported from legs 28 pivoted on bushings 29 which serve as the journals for the cam-shaft 5. 45 Connected at one end to the crosshead 23 is a traverse-rod 30 carrying the thread-guide 25 at its outer end. The traverse-rod 30 slides in a guideway in the traverse-frame 26 and the thread-guide 25 bears against a plate 31 thereon to adapt 50 it to traverse back and forth in parallel relation to the axis of the winding-spindle. The construction and arrangement of the parts of the machine as thus far described are well known to those versed in the art, being common to the 55 present type of winder. The only alteration necessary to the machine to adapt the present attachment or device for cooperation therewith is a slight change in the form of the guide-plate or traverse-frame back 31. As shown in Fig. 1, 60 the traverse-frame back 31 is cut away at 32 to accommodate the tapered head *h* of the spool, bobbin, or tube B, to be later described. The thread-guide 25 is notched at 24 to receive the 65 yarn and a wire thread-bail 33 mounted on the traverse-frame back 31 extends horizontally at the rear of the guide.

A tension-device, shown generally at 35 in Fig. 1 is supported from the frame 2 of the machine and arranged to adapt the yarn to draw 70 therethrough as it leads up from its source of supply. From the tension-device 35 the yarn draws upwardly across the thread-bail 33 and feeds through the notch 24 in the guide 25 as it is wound on the tube or bobbin B, see Fig. 4 of 75 the drawings.

The operation of the winding machine is controlled by a starting lever 36 acting through a rod 37 to disengage the driving pulley 8 from the clutch-member 9, and automatically-operated means are provided for arresting the winding 5 when the yarn breaks or the package reaches a predetermined diameter, such mechanisms being well known to those versed in the art and therefore not herein described in detail.

As before indicated, the present device is adapted 10 to wind a package on a spool, bobbin or tube comprising a barrel of cylindrical or slightly tapered form with a tapered or conical head at its end. Referring to Fig. 2, the tube B is herein shown as constructed of fiber or other suitable 15 material with a cylindrical barrel *b* and a tapering or frusto-conical head *h* inclined at substantially 45 degrees to the axis of the tube. The tube or bobbin B is rotated from the drive-shaft or winding-spindle 4, being carried on a sleeve 20 or hollow mandrel 40 slideable on an extension 41 of the spindle. Usually, the spindle-extension 41 is made separate from the shaft 4 and connected therewith by means of a shouldered stud 42 at its end having a threaded end 43 screwed into a 25 bore in the end of the spindle 4. Through this construction different types of spindles may be applied to the machine in accordance with the character of the package to be produced. It will therefore be seen that it is only necessary to 30 change the form of the spindle-extension in employing the present attachment on the winding machine.

The slideable sleeve or mandrel 40 is provided with a longitudinal groove or keyway 44 in its 35 bore engaged by a pair of keys 45 set into the spindle-extension 41, thus keying the mandrel to rotate with the winding-spindle 4. The outer end of the sleeve or mandrel 40 is counterbored to a larger diameter at 46, see Fig. 5, and driven 40 through the end of the spindle-extension 41 is a pin 47, the ends of which project into the counterbore. The ends of the pin 47 are thus adapted to engage the end of the counterbore 46 to limit the outward sliding movement of the sleeve or 45 mandrel 40 on the spindle-extension 41. The inward sliding movement of the mandrel 40 is limited by the engagement of its end with the side of a brake-wheel 48 fast on the end of the shaft or winding-spindle 4 and constituting a 50 usual part of the machine. This end of the sleeve 40 is formed with spaced radial flanges 49 which provide an annular groove 50 by means of which the sleeve 40 is slid on the spindle-extension 41.

A collar 51 is mounted for adjustment longitudinally on the sleeve 40, being provided with a set-screw 52 for securing it fast therewith. The collar 51 serves as an abutment for engaging within the conical head *h* of the bobbin B to regulate the position of the latter longitudinally of 60 the sleeve or mandrel 40. To secure the bobbin or tube B rotatively with the sleeve or mandrel 40 any suitable gripping means may be provided such as the bow-shaped springs 53 shown in Fig. 65.

The springs 53 may be made of a single length of wire having its ends bent to engage holes in the mandrel 40 and then extending longitudinally thereof in grooves 54 with portions 55 arched upwardly to provide the gripping means, it being 70 noted that the U-shaped end 56 of the spring extends diametrically across the end of the mandrel. The tube or bobbin B is simply slipped onto the sleeve or mandrel 40 to compress the springs 53, thereby causing them to bite into the mate- 75

rial of the tube to secure the latter both rotatively and longitudinally of the mandrel.

The present type of winding machine is usually constructed in separate units mounted on a table or bed 60, shown in Fig. 1, which is supported from the floor by legs 61. The several aligned heads or winding units are connected at the top by a pair of horizontal tie-rods 62 passing through lugs 63 integral with the frames 2.

10 In the present form of construction of the device the tie-rods 62 are employed as a convenient means for mounting the attachment; it being understood, however, that any other suitable arrangement may be employed for attaching the device to the machine, such as a bracket fastened directly to the frame 2.

As shown most clearly in Figs. 1, 4 and 5 the present mounting for the device comprises a bracket 64 extending across and beneath the two tie-rods 62 and secured thereto by means of clamps 65 bound against the top of the rods by bolts 66 and nuts 67. At its outer end the bracket 64 has an elbow-shaped arm 68 formed with a bearing hub 69 for supporting the operating lever 70 for the slidable mandrel 40.

Referring now to Figs. 2 and 3, the bell-crank lever 70 which operates to slide the mandrel 40 longitudinally of the winding-spindle is pivotally mounted on the bearing hub 69 of the bracket 64. 30 The lever 70 may be of unitary construction, but as herein shown I prefer to make it in two parts so that its arm 71 which carries the roller 85 for contacting with the winding may be lifted away from the mandrel 40 to facilitate placing 35 the bobbin B thereon and removing the completed package therefrom.

Referring to Figs. 2 to 5, inclusive, the opposite arm 72 of the lever 70 is formed with a hub portion 73, in which is secured a rod or shaft 75 extending downwardly through the hub 69 on the bracket 64. A set-screw 74 or any other suitable means may be employed for securing the hub 73 fast to the rod 75. The rod 75 extends some distance below the hub 69 and carries 45 a collar 76 secured fast on its lower end by means of a set-screw 77. A helical spring 78 is coiled around the rod 75 with one end secured in a hole in the collar 76 and its upper end engaging a hole in the under side of the hub 69. The spring 78 is thus held under torsion, tending to swing the bell-crank lever 70 in a clockwise direction, as viewed in Figs. 2 and 3 of the drawings, to maintain the roller 85 bearing against the yarn mass during the winding. By turning the collar 76 on the rod 75 the tension of the spring may be adjusted to effect a light contact of the roller on the yarn without undue pressure applied thereto.

The outer end of the arm 72 of the lever 70 is bent downwardly to reach in under the spindle-extension 41 and swiveled thereto is a block 80 engaging the groove 50 between the annular flanges 49 at the rearward end of the sleeve or mandrel 40. It will thus be observed that the spring 78 controls the bell-crank lever 70 to initially locate the mandrel 40 in its rearward position with its end abutting the side of the brake-wheel 48 as shown in Fig. 2 of the drawings.

The bell-crank lever 70 is swung in the opposite direction to slide the sleeve 40 outwardly on the winding-spindle under the action of the roller 85 on the end of the arm 71. The arm 71 is relatively fixed in lateral relation to the arm 72 but is hinged to the side of the hub 73 of the bell-crank to adapt it to swing upwardly in a

substantially vertical plane. For this purpose the arm 71 is formed with a hub 81 through which extends a stud 82 screwed into the hub 73. A finger or lug 83 projecting from the side of the arm 71 is adapted to engage against the flat top of the hub 73 to limit the downward swinging movement of the arm 71 under the action of gravity. The lug 83 is also arranged to engage across the top of the hub 73 when the arm 71 is swung upwardly into the position shown in Fig. 5 to maintain the roller 85 out of the way during the placing of the bobbin B on the mandrel 40 and the doffing of the package therefrom.

Swiveled to the outer end of the arm 71 is a bifurcated member or yoke 84 between the arms of which the contact-roller 85 is journaled. The roller 85 is preferably constructed of molded plastic material, such as a phenolic condensation product, having a surface which may be polished to a high degree of smoothness. Friction-reducing bushings 86 set into counterbores at the ends of the roller 85 are bored to receive a shaft or spindle 87 extending between the arms of the yoke 84. This form of mounting provides substantially frictionless journals for adapting the roller 85 to rotate freely; which is a most important consideration in order to relieve the yarn mass from any undue friction or abrasion during the winding. It is also to be noted that the 30 roller 85 is relatively short as compared to the length of the package to reduce its area of contact therewith. The yoke 84 has a hub 88 pivoted to the end of the arm 71 by means of a stud 89, the swiveled connection thus provided 35 permitting the proper contact of the roller with the winding as the bell-crank lever 70 swings on its pivot. A handle 90 projects rearwardly from the hub 88 on the yoke 84 to serve as a convenient means for lifting the arm 71 to carry the 40 roller 85 into raised position as shown in Fig. 5.

A lug or projection 92 on one arm of the yoke 84 is arranged to strike against the arm 71 of the bell-crank lever 70 to limit the rocking motion of the yoke on its pivot 89 when the arm and roller 45 are raised into the position shown in Fig. 5.

Having now described the construction and arrangement of the package-forming device in connection with the winding mechanism, the method of operation of the complete machine 50 will be next explained. To prepare the machine for winding a package of the prescribed shape the tube or bobbin B is slid onto the mandrel 40 until its head brings up against the collar 51 to locate it in position. As the bobbin B is applied 55 to the spindle the bow portions 55 of the wire springs 53 are compressed while being caused to bite into the interior of the barrel b of the bobbin to secure it rotatively and longitudinally of the mandrel 40.

Previous to applying the bobbin B the roller 85 is raised into the position shown in Fig. 5 by swinging the arm 71 upwardly on its pivot 82, the operator grasping the handle 90 for this purpose. Likewise, the traverse-frame 26 is swung back on 65 its pivots to withdraw the thread-guide 25 from proximity to the winding-spindle. The purpose of thus adjusting the parts is to avoid obstructing the head of the bobbin B in placing the latter on the winding-mandrel.

After the bobbin B is in place the arm 71 is lowered to bring the roller 85 into position with its surface substantially in contact with the periphery of the barrel b of the bobbin B; the lug 83 on the arm 71 serving as a stop to retain the 75

arm in substantially horizontal position. The traverse-frame 26 is then swung back on its pivots to place the thread-guide 25 against the opposite side of the barrel *b* of the bobbin B, it being observed by reference to Figs. 2 and 3 of the drawings that the upper button-portion of the thread-guide 25 is beveled off on one side at an angle corresponding to the inclination of the head *h* of the bobbin so that the guide may move 10 into proximity therewith.

The machine is threaded by drawing the yarn *y* from its source of supply, leading it through the tension-device 35, and drawing it upwardly therefrom across the wire-bail 33 and down 15 through the notch 24 in the thread-guide 25. The end of the yarn is made fast to the barrel *b* of the bobbin B and the machine is ready for operation.

The operator rocks the starting lever 36 to 20 engage the clutch member 9 with the driving pulley 8, whereby to set the winding-spindle 4 in motion, and the cam-shaft 5 is driven therefrom through the connections previously described. As the cam 20 is rotated by the shaft 5 it reciprocates the crosshead 23 to impart traversing motion to the thread-guide 25 which slides on the traverse-frame 26. As the guide 25 is traversed along the barrel *b* of the bobbin B the yarn is deposited thereon in helical coils, reversing at 25 each end and building up layers by that system known as the "Wardwell" or V-wind.

As a layer of yarn is formed on the barrel *b* of the bobbin B its contact with the roller 85 rotates the latter while tending to force it rearwardly away from the axis of the winding-spindle. The bell-crank lever 70 is so proportioned that as 30 each yarn layer is completed the movement of the roller 85 will cause the arm 72 of the bell-crank to shift the mandrel 40 outwardly along the spindle-extension 41 to an extent sufficient to cause 35 the next layer of winding to be stepped to the right, as viewed in Fig. 2, so that its end will conform to the tapered or conical periphery of the head *h* on the bobbin B. The movement of the arm 72 is transmitted to the mandrel or sleeve 40 through the block 80 engaging the annular groove 50 in the end of the mandrel, it being understood 40 that this form of connection permits the mandrel to rotate with the winding-spindle while sliding 45 thereon.

The winding continues in the manner as above explained with the mandrel 40 and bobbin B being gradually displaced to the left, as viewed in Figs. 2 and 3, during and proportionate with the growth 55 of the wound mass so that the layers of winding are stepped back from the forward end of the package P to form the latter with a conical or tapered end, see Fig. 3 which illustrates the package at or near the point of completion.

60 As herein illustrated the completed package P has its end tapered at an angle of substantially 45 degrees in conformity with the inclination of the conical head *h* of the bobbin; but it is to be understood that packages of other proportions may 65 be wound with the present device or attachment by varying the shape of the spool, bobbin or tube and altering the proportions of the two arms of the bell-crank lever 70. That is to say, bell-crank levers having arms of different proportions may 70 be employed in place of the one herein shown, the bracket 64 being adjustable with respect to the axis of the winding-spindle to provide for such changes. For some purposes a bobbin or tube having a tapered barrel is used and the present 75 device may be employed for winding the package

thereon by simply changing the form of the mandrel or holder.

After the winding has been completed the roller 85 is lifted out of the way, the traverse-frame 26 moved back to release the guide 25 from the surface of the winding and the package may then be withdrawn from the mandrel 40 and another bobbin or yarn-carrier placed thereon to continue the operation of the machine.

It will be observed from the foregoing that the present improved device or attachment is entirely automatic in its operation to form or shape the package as required without care or attention on the part of the operator. In setting the device at the start of the winding all that is required is to 15 place the roller 85 against the barrel of the bobbin B, there being no sliding parts or other elements requiring adjustment.

It will be noted further that the mechanism for shifting the bobbin or package during the winding is of the utmost simplicity, comprising practically only one element, the bell-crank lever which is rocked during the growth of the yarn mass. Thus, the numerous articulated levers, links, slides, gears and other impedimenta of previously used devices are entirely eliminated, not only to lessen the cost of manufacture of the apparatus, but further and most important, to reduce the friction and eliminate wear. The elimination of friction results in placing less pressure 30 on the yarn mass being wound and the use of the rotatable roller as a contact element prevents rubbing and abrasive action which would have a deleterious effect on fine, soft materials.

Due to the simple arrangement of the parts and 35 the avoidance of complicated joints and sliding connections the contact-roller exerts but very little pressure on the mass being wound and consequently there is no tendency to compress the layers and cause bulging at the end of the package 40 as would be liable when winding soft yarns. The reduction in the number of pivots, joints and sliding connections also reduces wear on the parts so that the mechanism is more durable in use and less liable to deterioration from shackle joints 45 which might destroy its accuracy and reliability in forming the package.

While I have herein described and illustrated a preferred form of construction of the device, it is to be understood that certain modifications may 50 be made in the structure and arrangement of the parts thereof without departing from the spirit or scope of the invention. Therefore, without limiting myself in this respect, I claim:

1. In a winding machine, means for rotating 55 a yarn-carrier, means for traversing yarn longitudinally thereof, and means for progressively displacing the yarn-carrier axially during the winding comprising a bell-crank lever directly connected to the carrier, and means carried on 60 and movable bodily by and with the growth in the winding to operate the lever to move the carrier.

2. In a winding machine, the combination of 65 means for rotating a yarn-carrier, means for traversing yarn longitudinally of the carrier, a bell-crank lever directly connected to the carrier to slide the latter in the direction of its axis, and a roller journaled on said bell-crank lever and arranged to bear against the yarn wound on the 70 carrier to rock the lever to slide the carrier to be moved bodily by the growth in the winding.

3. In a winding machine, the combination of 75 a rotatable and longitudinally movable yarn-carrier provided with a frusto-conical head,

means for rotating the carrier, means for traversing yarn to deposit it in helical coils on the carrier, a pivoted lever directly connected to the carrier, and means on said lever for contacting with the yarn wound on the carrier to cause it to be displaced bodily to rock the lever to move the carrier during the growth in the winding.

5 4. In a winding machine, the combination of means for rotating a yarn-carrier, means for traversing yarn longitudinally of the carrier, a pivoted bell-crank lever having one arm directly connected to the carrier to displace the latter in the direction of its axis, and a roller on the opposite arm of the bell-crank lever adapted to bear 10 against the yarn wound on the carrier to be moved bodily under the influence of the increase in diameter of the winding to rock the lever to move the carrier.

15 5. In a winding machine, the combination of a rotatable spindle, a yarn-carrier rotatable with the spindle and slidable longitudinally thereof, means for traversing yarn longitudinally of the carrier, a lever directly connected with the carrier to slide the latter longitudinally of the spindle, and means carried by said lever and arranged to bear against the yarn wound on the carrier to cause it to be bodily displaced by the growth in the winding to rock the lever to slide the carrier without applying undue pressure or friction 20 on the yarn.

25 6. In a winding machine, the combination of a winding-spindle, a mandrel rotatable with the spindle and slidable axially thereof, means for securing a yarn-carrier rotatively with said mandrel, means for traversing yarn longitudinally of the carrier, a bell-crank lever having one arm directly connected to the mandrel to slide the latter on the spindle, and means on the opposite arm of the bell-crank lever for lightly contacting 30 the yarn wound on the carrier to cause said means to be moved bodily by the growth in the winding to rock the lever to slide the mandrel.

35 7. In a winding machine, the combination of a rotary winding-spindle, a mandrel rotatable with the spindle and slidable axially thereof, means for securing a yarn-carrier on the mandrel, means for traversing yarn longitudinally of the carrier, a bell-crank lever directly connected with the mandrel to slide the latter, means on 40 said lever for contacting the yarn wound on the carrier to cause said means to be displaced bodily away from the mandrel to rock the lever to slide the mandrel during the growth of the package wound on the carrier, and resilient means for 45 resisting the sliding movement of the carrier.

50 8. In a winding machine, the combination of a rotatable and longitudinally movable yarn-carrier, means for rotating the carrier, means for traversing yarn longitudinally of the carrier, a sleeve for sliding the carrier in the direction of its axis, a bell-crank lever having one arm directly connected to the sleeve, and means on the opposite arm of the bell-crank lever for contacting with the yarn wound on the carrier to cause 55 said means to be displaced bodily by the growth in the winding to rock the lever to slide the sleeve.

55 9. In a winding machine, the combination of means for rotating a yarn-carrier, means for traversing yarn longitudinally of the carrier, a bell-crank lever having one arm directly connected to the yarn-carrier to slide the latter longitudinally, means on the opposite arm of the bell-crank lever adapted to contact with the winding to cause it to rock the lever to slide the

carrier, and means for mounting said contact means to adapt it to be displaced manually without sliding the carrier whereby to facilitate the placing and removal of the yarn-carrier.

10 10. In a winding machine, the combination of a rotatable winding-spindle, a sleeve rotatable with and slidable on the spindle, said sleeve formed with an annular groove, means for rotatably supporting a yarn-carrier to slide with the sleeve, a bell-crank lever, means on one arm 10 of the bell-crank lever engaging the groove in the sleeve to slide the latter, and means on the opposite arm of the bell-crank lever for contacting with the yarn wound on the carrier to cause said means to be moved bodily by the growth in 15 the winding whereby to rock the lever to slide the carrier.

11. In a winding machine, the combination of a winding-spindle, a mandrel slidable longitudinally of the spindle, means for securing a yarn- 20 carrier to rotate with the mandrel, a two-part pivoted bell-crank lever having one of its arms connected to slide the mandrel, the opposite arm of the bell-crank lever being hinged to adapt it to swing in a plane substantially parallel with 25 the axis on which the lever is pivoted, and means on said last-named arm adapted to contact the yarn wound on the carrier to rock the lever to slide the mandrel, said hinged arm adapting said contact means to be displayed with respect 30 to the mandrel to facilitate placing the carrier thereon and its removal therefrom.

12. In a winding machine, the combination of a winding-spindle, a yarn-carrier slidable longitudinally of the spindle, a bell-crank lever for 35 sliding said carrier, and means on said bell-crank lever for contacting with the winding to rock the lever, said bell-crank lever being movable about a fixed pivot to slide the carrier and having its arm carrying the contact means hinged to swing 40 in a plane at right-angles to its rocking movement about the fixed pivot to remove the contact means from proximity with the spindle.

13. In a winding machine, the combination of a rotatable winding-spindle, a mandrel rotatable 45 with and slidable axially of the spindle, a pivoted bell-crank lever having one arm connected to slide the mandrel, means on the opposite arm of the bell-crank lever for contacting with the yarn wound on the carrier to rock the lever, and 50 a hinged joint between the first arm and the second arm of the bell-crank lever for permitting the contact means to be swung upwardly to remove it from proximity with the mandrel to 55 facilitate the placing of the carrier thereon and its removal therefrom.

14. In a winding machine, the combination of a rotary spindle, a mandrel rotatable with and slidable axially of the spindle, a pivoted arm, means at the end of the arm engaging the mandrel to slide the latter, a second arm connected to rock the first arm on its pivot and having a secondary pivot to adapt it to be rocked in a plane extending across the plane of movement of the first arm, and means on the second arm 65 for contacting with the winding to rock the first arm to slide the mandrel.

15. In a winding machine, the combination of a rotatable and longitudinally movable yarn-carrier, means for rotating the carrier, means for 70 traversing yarn longitudinally of the carrier, a pivoted bell-crank lever having one arm directly connected to the carrier to move the latter in the direction of its axis, means on the opposite arm of the bell-crank lever adapted to con- 75

tact the yarn wound on the carrier to cause said means to be moved bodily during the growth in the winding to rock the lever, and a spring operative to resist the movement of the bell-crank lever by the contact means.

5. 16. In a winding machine, the combination of a rotatable and longitudinally movable yarn-carrier, means for rotating the carrier, means for traversing yarn longitudinally of the carrier, a 10 pivoted bell-crank lever having one arm directly connected to the carrier to move the latter in the direction of its axis, means on the opposite arm of the bell-crank lever adapted to contact the yarn wound on the carrier to cause said means to be moved bodily during the growth in the winding to rock the lever, a spring acting to 15 resist the swinging of the bell-crank lever by the

contact means, and means for adjusting the tension of the spring.

17. In a winding machine of the type having a rotating spindle and a thread guide reciprocating longitudinally thereof; a bobbin receiving 5 sleeve slideable on the spindle, a bell crank pivotally secured adjacent the spindle, a connection between one arm of the bell-crank and the sleeve, a member carried by the other arm of the bell-crank and resting directly on the thread 10 mass, whereby the sleeve will be moved longitudinally of the spindle and independently of the movement of the thread guide as the thread mass on the bobbin increases in diameter, and a spring tending to keep said member in contact with the 15 thread mass.

EDWARD F. PARKS.

Patent No. 2,022,572.

EDWARD F. PARKS.

It is hereby certified that error appears in the printed specification of the above numbered patent requiring correction as follows: Page 4, second column, line 71, claim 2, beginning with the word "to" third occurrence, strike out all to and including the word "winding" in line 72, and insert the same after "carrier" second occurrence, in line 71; page 5, second column, line 30, claim 11, for "displayed" read displaced; and that the said Letters Patent should be read with these corrections therein that the same may conform to the record of the case in the Patent Office.

Signed and sealed this 14th day of January, A. D. 1936.
